UNITED STATES PATENT OFFICE

JOHN A. FALVEY, OF DETROIT, MICHIGAN

MAILING DEVICE

Application filed June 27, 1929. Serial No. 374,064.

This invention relates to mailing devices, and more particularly to one comprising a body of paste-board, paper, parchment or suitable fabric which may be folded upon itself to form an enclosure in which the article or material to be transported may be housed.

It is an object of the invention to provide a device of this character which is simple in construction, easy to manipulate, economical to fabricate, but highly effective for the purpose intended.

It is a special object to provide a mailing device which contains a minimum number of flaps or stubs, and one which, when in folded operative condition for mailing, will provide a completely sealed compartment, free from the atmosphere for containing the material to be shipped.

It is a further special object to provide a mailing or shipping device of the above described character, having a structure which, while accomplishing the objects already set forth nevertheless permits of easy and ready opening of the compartment for removal of the articles or material contained therein, and without the necessity of unduly disrupting the material from which the device is made.

A still further object of the invention is to provide the foldable flap or stub portion which cooperates with the main body of the device with an adhesive disposed thereon in such fashion as to leave unsealed portions between the flap and body immediately adjacent the outside margin of the flap, whereby to permit the easy insertion of a tool or implement between the flap and body for breaking the seal therebetween and for loosening the flap from the body without danger of tearing or unduly disrupting the material from which the parts are made.

In prior devices, considerable difficulty has been experienced in maintaining an effective seal between the parts while at the same time presenting a substantially smooth unbroken exterior for the device and providing means for readily opening the compartment or pocket containing the enclosed article or materials, and it is an especial object of this

invention to incorporate all of these desirable features into a simple device for the purpose intended.

These and other objects of the invention will appear from the following description and the appended claim when taken in conjunction with the drawing, forming a part of this application and in which,

Figure 1 is a plan view of the device with the flap or stub in unfolded condition, showing one way of disposing the adhesive on the flap for carrying out the invention; Figure 2 is a similar view after the flap has been folded and glued to the body of the device for forming the sealed housing compartment and in condition for mailing or shipment; and Figure 3 is a transverse sectional view taken on the line 3—3 of Figure 2.

Referring specifically to the several views of the drawings in which the same reference characters denote corresponding parts, 1 designates the main body which as previously described, preferably consists of paste-board, heavy paper, parchment or similar material which may be folded upon itself without breaking the said material. A flap or stub 2 which may form an integral part of the body 1 is located at one end thereof, as illustrated in the drawing, a line of fold 3 defining the separation between what has been termed herein the body and flap.

The external margin of the flap 2 carries thereon a suitable adhesive 4, such as ordinary glue, which adhesive extends throughout the entire border of the flap from the point 3' of the line of fold across the free end of the flap to the point 3" at the opposite end of the line of fold. While the adhesive extends completely around the border of the flap and projects up to the line of fold at each side thereof, the adhesive is omitted at predetermined portions, immediately adjacent the outer margin of the flap as at 5 and 5'. This may be very effectively accomplished by forming the area covered by the adhesive with rounded terminals, such as shown at 6 and 6', thus carrying the adhesive completely to the line of fold 3 while at the same time leaving blank or uncovered portions at 5 and 5', immediately adjacent

both the external margins of the flap as well as the line of fold itself, all for a purpose which will hereinafter more fully appear.

The device is used in the following manner:

- 10 The flap or stub 2 is bent towards the body 1 along the line of fold 3 in an obvious fashion, after wetting the adhesive or glue 4 to render it effective as with the glued flap of an ordinary envelope. The article or material to be transported is placed between the body and flap so as to occupy the space defined by the areas covered with the adhesive and the line of fold, and the flap and body are then firmly pressed into intimate contact and held until the parts firmly adhere to each other. At this stage the parts assume the condition illustrated in Figure 2 of the drawing.
- 20 It is apparent because of the fact that the adhesive or glue extends completely to the line of fold 3 that when the flap and body are glued together in the manner just described, the space within which the material for shipment has been placed, will form a compartment sealed from the atmosphere for housing the said material. This is particularly valuable for the purpose of transporting various materials as well as very small or finely powdered ones, so as to eliminate danger of escape thereof from the container. It is perfectly obvious, however, that while of especial value in connection with small or powdered materials, the device is not restricted to such use as it lends itself just as readily for the transportation of larger articles, such as coins, paper specie, and the like, for which purpose it is very effective.
- 30 In order to remove the articles or materials contained in the compartment of the device, it is merely necessary to insert a pointed instrument of any suitable nature between the flap and body at the unglued portions provided by the spaces 5 or 5', forcing the said instrument inwardly towards the sealed compartment under the guiding action of such unglued portions until the seal is broken, then continuing to separate the flap from the body in the ordinary manner customary in this art. By providing the small pockets, however, for the initial reception of the instrument to be used for breaking the seal between the flap and body, and utilizing the same for their continued guiding action upon the instrument as it is further projected to completely break the seal, danger of tearing or unduly disrupting the material

from which the device is made in an undesirable fashion is entirely eliminated.

By disposing the unglued portions or sprockets immediately adjacent the line of fold 3, as well as at the margin of the flap, it is obvious that an additional guiding action for the breaking instrument is secured by means of the bend itself at the line of fold. When used in this manner it is apparent that if a sharp edged instrument is used the device may be readily cut along the line of fold by projecting the instrument entirely throughout the width of the device, if this result is desired, rather than simply separating the flap from the body solely throughout the area covered by the adhesive and without tearing or disrupting the materials constituting the device.

By extending the adhesive completely to the exterior or outer margins of the flap, except at the unglued portions left to form the breaking pockets described, a very neat and smooth-edged union is formed throughout substantially the entire contacting areas of the flap and body.

While the preferred embodiment of the invention has been illustrated and described, in which the width of the flap 2 corresponds to that of the main body 1, in which the terminals of the area covered with adhesive are rounded, and in which the plain unglued portions are located immediately adjacent the line of fold 3, it is obvious that many variations from these specific features may be made without departing from the spirit of the invention. In other words, the flap 2 may be of less width than the body 1, the ends of the glued area adjacent the line 3 may be of various shapes, and the unglued portions such as 5, 5' for forming the breaking pockets may be located at various points along the exterior or outer margin of the flap 2. It is therefore not intended to limit the scope of the invention beyond that defined by the appended claim.

I claim:

A mailing device comprising a sheet, a flap at one end thereof foldable upon the sheet, said flap having adhesive material extending completely around all the free edges thereof so that when folded a completely closed pocket is formed between the flap and sheet, adapted to receive an article for mail, the adhesive material being partly omitted adjacent the ends of the fold to form entering spaces, permitting the insertion of a blade to cut the fold.

JOHN A. FALVEY.
